US00D996594S

(12) **United States Design Patent** (10) **Patent No.:** **US D996,594 S**
(45) **Date of Patent:** **** Aug. 22, 2023**

(54) **ELECTROMAGNETIC FIELD GENERATOR**

(71) Applicant: **Stryker European Holdings I, LLC**,
Kalamazoo, MI (US)

(72) Inventors: **Fabian Riegelsberger**, Umkirch (DE);
Florian Herrmann, Schwanau (DE)

(73) Assignee: **Stryker European Operations Holdings LLC**, Kalamazoo, MI (US)

(**) Term: **15 Years**

(21) Appl. No.: **29/752,908**

(22) Filed: **Sep. 29, 2020**

Related U.S. Application Data

(63) Continuation of application No. 29/673,442, filed on Dec. 14, 2018, now Pat. No. Des. 901,661.

(57) **CLAIM**

The ornamental design for an electromagnetic field generator, as shown and described.

DESCRIPTION

FIG. 1 is a top, front left perspective view of an electromagnetic field generator showing our new design;

FIG. 2 is a front end view thereof;

FIG. 3 is a rear end view thereof;

FIG. 4 is a top plan view thereof;

FIG. 5 is a bottom plan view thereof;

FIG. 6 is a right side view thereof; and,

FIG. 7 is a left side view thereof.

In the drawings, the broken lines show unclaimed portions of the electromagnetic field generator that form no part of the claimed design.

1 Claim, 5 Drawing Sheets
